DESIGN FOR A BUCKLE

Charles M. Blankmann, St. Louis, Mo.

Application February 3, 1936, Serial No. 60,965

Term of patent 7 years

To all whom it may concern:

Be it known that I, Charles M. Blankmann, a citizen of the United States, residing at St. Louis, Missouri, have invented a new, original, and ornamental Design for a Buckle, of which the following is a specification, reference being made to the accompanying drawing, forming a part thereof, in which Figure 1 is an edge view and Figure 2 is an elevational view of a buckle embodying my design.

I claim:

The ornamental design for a buckle, substantially as shown.

CHARLES M. BLANKMANN.
